UNITED STATES PATENT OFFICE

KATHARINE H. OBER, OF BALTIMORE, MARYLAND

DESIGN FOR A BAKING UNIT OF A WAFFLE MOLD

Application filed May 16, 1930. Serial No. 35,673. Term of patent 14 years.

To all whom it may concern:

Be it known that I, KATHARINE H. OBER, a citizen of the United States, residing at Baltimore city, in the State of Maryland, have invented a new, original, and ornamental Design for Baking Unit of a Waffle Mold, of which the following is a specification.

Reference is had to the accompanying drawings which form a part of the specification, as follows:

Fig. 1 is a plan view of the baking unit, showing my new design.

Fig. 2 is an edge view of the baking unit.

I claim:

The ornamental design for a baking unit of a waffle mold, as shown.

In testimony whereof I affix my signature.

KATHARINE H. OBER.
